WRINGER ACTUATING MECHANISM

Sidney S. Holland, Gard F. Traughber, and Reuben J. McVey, Kansas City, Mo., assignors, by direct and mesne assignments, of one-half to Oscar Rieger and one-half to said Sidney S. Holland, both of Kansas City, Mo.

Application February 16, 1934, Serial No. 711,558

12 Claims. (Cl. 74—387)

Our invention relates to driving mechanism, and more particularly to mechanism of that character for use in connection with domestic washing machines of motor driven, reversible, 5 swinging wringer type.

A washing machine of the type to which our invention relates usually includes an oscillating member located within the tub element of the machine for agitating wash water within the 10 tub and a wringer mounted on the tub or its base and adapted for operation in any of several positions to permit wringing of the cleansed articles from the wash water to a rinsing tub and from the rinsing tub back to the wash tub, or 15 to a basket, both the agitator and wringer being driven from a single motor mounted on the tub base.

Numerous mechanisms have been devised for transforming rotary motion of the motor shaft to reciprocatory motion for oscillating the washing agitator, and our invention is not so much concerned with that part of the machine, its principal object being to provide simple and efficient means for actuating the wringer selectively in either direction from a single source of power 20 when in any position about its mounting axis, and for combination of the wringer and its driving mechanism with the tub in a manner to avert tendency of the tub to tip under weight of the wringer.

In accomplishing these and other objects of the invention, we have provided improved details of structure, the preferred forms of which are illustrated in the accompanying drawings, wherein:

Fig. 1 is a perspective view of a washing machine and its wringer equipped with driving mechanism embodying our invention.

Fig. 2 is a horizontal plan view of the tub support or base on the line 2—2, Fig. 1, part of the gear housing being shown in section to better illustrate the device.

Fig. 3 is an enlarged detail perspective view of a part of the tub, wringer and driving mechanism, 45 particularly illustrating the wringer reversing and position locating elements.

Fig. 4 is an enlarged, central, vertical section of the mechanism for transmitting power from the wringer driving shaft to the wringer roll shaft for selectively operating the wringer in either direction, showing the parts in position for driving the wringer forwardly.

Fig. 5 is a view similar to Fig. 4, but showing the parts in position for driving the wringer re- 55 versely.

Fig. 6 is a transverse section on the line 6—6, Fig. 4, particularly illustrating the coupling between the upper universal joint and the transmission shaft.

Fig. 7 is a horizontal section on the line 7—7, Fig. 5, particularly illustrating the cam mechanism, whereby direction of operation of the wringer is selectively determined.

Fig. 8 is an enlarged detail perspective view of the cam collar and its operating handles. 10

Fig. 9 is a detail perspective view of the housing for the upper universal joint, showing parts of the joint in spaced relation for better illustration.

Fig. 10 is a cross section on the line 10—10, Fig. 15 4, particularly illustrating mounting of the driven pin of the lower universal joint.

Fig. 11 is a vertical section on the irregular line 11—11, Fig. 5, illustrating one of the universal joint couplings and mounting of the lower joint 20 housing on the tub.

Referring more in detail to the drawings:

1 designates a tub of ordinary domestic washing machine type mounted on a base 2 of ordinary construction, comprising a bed ring 3 supported by spaced legs 4, preferably arranged in diametric pairs and provided with caster wheels 5. The tub is adapted for containing an agitator of dolly or other well-known type (not shown) adapted for oscillation by a shaft 6 suitably extended through the bottom of the tub and connected with a main driving shaft 7 operable from a motor 8 in any suitable manner. Mounted adjacent the bottom of the tub, preferably on the bed ring 3, is a gear housing 9 containing a worm gear 10, (Fig. 2) operable from a worm 11 on the main driving shaft 7. Operable from the worm gear, by a cam 12 or other suitable means, is a pitman 13 having transmission 14 for oscillating the agitator shaft 6 when the motor is 40 active.

The driving parts just described, including the motor, form no part of our present invention and are, therefore, described in only sufficient detail to indicate operation of the washing mechanism 45 as distinguished from the wringer operating mechanism to which the invention is particularly directed.

Extending from the top of the gear housing 9 is a vertical, tubular housing 15 containing a driving shaft 16 which is fixed to the worm wheel 10 to rotate synchronously with oscillation of the washing agitator, although adaptable for operation independently thereof. Mounted on the top of the tubular housing 15 is an elbow housing 17 55

preferably of split construction to permit access to a universal joint indicated generally at 18.

The universal joint 18 includes a driving pin 19 journaled in a split bearing 20 mounted in the 5 horizontal leg of the elbow housing 17, the pin 19 having a stop collar 21 on its power end and having a reduced extension 22 at its outer end projecting beyond the end of the bearing 19, on which a pinion 23 is keyed, preferably by a pin 10 24. Mounted on the split bearing 20 by means of a collar 25 and attached to the side of the tub 1 by a boss 26 and by a boss 27 extending from 15 the elbow housing 17 is a gear housing 28 including a body portion 29 enclosing the driving pinion 15 23 and driven beveled gear wheels presently described, the terminals 30 and 31 of the housing being of particular construction for adapting the housing to the purposes of our invention, the gear housing being attached to the elbow housing 20 17 by cap screws 32 projecting loosely through ears 33 on the elbow housing into threaded sockets in ears 34 on the gear housing.

Extending centrally through the gear housing 28 is a vertical transmission shaft 35 having its 25 lower end longitudinally movable in a socket 36 in the lower housing terminal 30 and its upper end slidably projected through a bearing aperture 37 in the cover plate 38 at the top of the upper terminal of the gear housing into a chamber 39 30 formed by an upstanding annular flange 40 on and integral with the cover plate 38. Mounted on the shaft 35, preferably by pins 41, are upper and lower beveled gear wheels 42 and 43 adapted 35 for selective engagement with the pinion 23 to effect rotation of the transmission shaft in either direction in response to constant rotation of the driving shaft 16.

Selective engagement of the gear wheels 42 and 43 with the pinion 23 is preferably effected 40 by fixing the gear wheels on the shaft by the pins 41, previously mentioned, and by longitudinally shifting of the transmission shaft through cam mechanism including pins 44 extending radially from a collar 45 on the shaft 35 45 above the upper beveled gear and retained in engagement therewith by a thrust washer 46 fixed on the shaft by a pin 47, the pins 44 preferably consisting of cylindrical studs having shanks 48 threaded into sockets 49 in the collar 45, and 50 extended through vertical slots 50 in a cylindrical extension 51 on the housing body 29. Rotatably mounted in an annular seat 52 counter-sunk in the outer surface of the extension 51 is a split collar 53 having inclined, slightly arcuate cam 55 grooves 54 in its inner surface (Fig. 8), into which the outer ends of respective pins 44 are projected, the pins 44 being preferably provided with rollers 55 to afford anti-friction bearing of the pins on the edges of the vertical slots 50 and on inclined, 60 slightly arcuate edges of the cam grooves 54, thereby facilitating shifting action of the shaft 35.

The split portions of the collar are secured about the extension 51 by stud bolts 57 projecting 65 through ears 58 on the collars, and having a nut 59 threaded on the end thereof.

The collar 53 is provided with handles 60 of a number and so located about the collar as to provide ready access to an operator of the washing machine standing in any of the customary 70 positions relative to the machine, and is retained in any of its selected positions by a spring-pressed ball 61 slidably mounted in a bore 62 in the collar and engageable in a series of sockets 63 formed in the periphery of the sleeve 51.

Rotatably mounted about the annular flange 40 and in an arcuate groove 64 in the top of the cover plate 38, for support therein, and preferably resting on the top edge of the annular flange, is the shank 65 of an upper elbow housing 66 constituting a direct support for the wringer mechanism, the shank 65 being readily removable from and replaceable on the upper terminal of the gear housing when the wringer is to be separated from the machine for shipment, storage or repairs and 10 readily replaced on the terminal for reassembly with the machine.

Slidably extending through and rotatably mounted in a bearing 67 at the upper end of the shank 65 is the stub shaft 68 of an upper universal joint, the stub shaft 68 having a coupling pin 69 projected diametrically from its lower end to removably seat in a jaw 70 located within the chamber 39 and formed on a collar 71 keyed to the upper end of the transmission shaft 35 by a pin 72, the upper end of the jaw 70 preferably terminating below the top of the cup so that the jaw may be completely housed when the upper elbow housing 66 is in place.

The stub shaft 68 is provided at its upper end 25 with a yoke member 73, including a collar 74 constituting a stop or keeper and adapted for flexible connection with the similar collar 75 of a stub shaft 76 rotatable in a bearing 77 within the upper horizontal portion of the elbow housing 66, 30 the outer end of the stub shaft 76 terminating within a chamber 78 in the end of the elbow housing and provided with a coupling pin 79 adapted to seat in the jaw 80 of a coupling collar 81 on the end of one of the roller shafts 82 of 35 wringer mechanism 83 mounted on a flange 84 on the elbow housing 66, preferably by means of cap screws 85.

The horizontal portion of the elbow housing 66 is of split construction to permit access to the 40 universal joint mechanism contained therein.

In assembling the wringer mechanism with its elbow housing the coupling jaw on the wringer shaft is moved over the coupling pin on the universal joint stub shaft 76 to establish the driving 45 connection, and when the wringer mechanism is to be mounted on the tub the elbow housing with the wringer mechanism on it is set over the annular flange on the transmission housing, the coupling pin on the universal joint finding its 50 seat in the jaw 70 of the transmission shaft to establish that driving connection.

The couplings for the stub shafts of the upper and lower universal joints are identical, each 55 preferably consisting of a sectional link 87 (Fig. 9) composed of two flat bars 88 having spacing bosses 89 on their inner faces intermediate their ends forming recesses 90 for trunnion blocks 91, each provided with oppositely directed trunnions 92 rotatably mounted in apertures 93 in the ends 60 of the bars 88, the bars 88 being connected by a stud bolt 94 extending through the bosses 89 to hold the bars securely together and having a head 95 counter-sunk in a socket 96 in one of the bars.

The blocks 91 are adapted to fit between ears 65 73 or 97 on the collars 74 or 75 of the stub shafts 68 or 76 of the upper joint, or between corresponding ears or like collars on the lower joint, and are provided with through openings 98 adapted for registering with corresponding openings 99 in the ears to permit passage of trunnion pins 100 through the ears and blocks so that the blocks may have pivotal movement on axes at right angles to the trunnion 92 to provide the universal connection between the shaft sections. 75

It is apparent that with the construction described the wringer roll shaft may be rotated in either direction when the wringer is in any position it may assume about the extended axis of the transmission shaft. In order to retain the wringer mechanism in any of the several positions at which it may be most conveniently located for receiving articles from the washing tub for delivery into the rinsing tub, from the rinsing tub either back to the washing tub or to a basket, or at a neutral position in which it is out of the way of the operator, I provide a latch for holding the wringer mechanism in either operating position or in neutral position.

The latch mechanism referred to preferably consists of a pin 101 slidably mounted in the base flange 102 at the bottom of the upper elbow housing and in a protuberance 103 on the base ring, the upper end of the latch pin being slidably guided in a socket 104 in a protuberance 105 on the side of the upper elbow housing and the lower end of the latch pin being adapted for projection into any of the sockets 106, 107 or 108 in the cover plate 38 according to position of the wringer; the sockets 106, 107 and 108 being duplicated in the side of the cover plate opposite the annular flange 40 to permit additional selective positions of the wringer relative to the tubs.

The pin 101 is operable by a finger piece 109 fixed to the pin and cooperative with a thumb hold 110 on the protuberance 105 so that the latch handle and thumb hold may be grasped with one hand while the operator employs the other to turn the wringer to adjusted position.

In order to avoid overbalancing of the tub and its base under weight of the wringer, particularly when the wringer is extended outwardly from the tub, we preferably arrange the gear housing 9 adjacent one of the base legs of the machine in order to locate the transmission housing 28 in substantially vertical alignment with such leg, so that the forces resulting from extension of the wringer outwardly from the tub will be transmitted downwardly in substantial alignment with the leg and the leg thus serve as a brace to prevent tipping of the machine. As the position of the wringer is changed and its moment increased, the relative moment of the tub and base is thus increased to stabilize the machine.

Assuming the driving mechanism to be constructed and assembled with the tub, the tub base and the wringer as described, and with the wringer arranged to take articles from the washing tub for delivery into a rinsing tub that may be located adjacent the washing tub (Fig. 1), the transmission gearing is set with the beveled gear wheel 43 in mesh with the driving pinion 23 so that the connected wringer roll is rotated forwardly relative to the washing tub and articles passed through the wringer will be delivered to the adjacent rinsing tub.

When, however, the wringer is to be operated in a reverse direction, the collar 53 is rotated about the sleeve 51 on the gear housing 28, the transmission shaft shifted downwardly, thereby disconnecting the lower beveled gear wheel 43 from the driving pinion and meshing the upper gear wheel with the pinion; rotation of the collar 53 moving the cam track 54 over the pins 44 on the collar 45 above the upper beveled gear wheel to lower the gear wheel and the transmission shaft to which it is attached; the vertical slots 46 in the sleeve 51 restricting movement of the pins to a vertical plane in response to movement of the inclined cam track 54 over the

pins. Upon initiation of movement of the collar 53 for shifting the transmission shaft, the ball latch 61 is moved out of its socket 63 in the sleeve 51 against the tension of its spring and held in its extended position by contact with the wall of the sleeve until the collar has been rotated to the next adjacent position, where the ball is forced into a corresponding socket to hold the collar in place; it being apparent that the gear wheels may be retained at either limit of their movement to effect rotation of the wringer in either direction, or in a neutral position at which the wringer is inoperative because of disengagement of both beveled gear wheels from the driving pinion.

The wringer mechanism is released for positioning in a different location by lifting the latch pin from the socket in which it is seated at that time, and retained in the desired location by automatic repositioning of the latch pin in a socket corresponding to that position.

When the wringer is in position to receive and deliver the articles as desired, power is transmitted from the motor to actuate the drive shaft, the worm and worm wheel, the lower universal joint, the transmission shaft, the upper universal joint, and the wringer, regardless of position of the wringer and in either forward or reverse direction, according to selected engagement of the beveled gears on the transmission shaft with the driving pinion on the lower universal joint.

What we claim and desire to secure by Letters Patent is:

1. In combination with a driving shaft, a transmission shaft offset laterally and in parallel relation with the driving shaft, a pinion connected with one of said shafts, gear wheels connected with the other shaft and selectively engageable with said pinion, means for effecting selective engagement of the pinion and gear wheels, and operating mechanism operatively connected with the transmission shaft.

2. In combination with a driving shaft, a transmission shaft offset laterally and in parallel relation with the driving shaft, a pinion connected with one of said shafts, gear wheels connected with the other shaft and selectively engageable with said pinion, cam mechanism for effecting selective engagement of the pinion and gear wheels, and operating mechanism operatively connected with the transmission shaft.

3. In combination with a driving shaft, a flexible joint operatively connected with the driving shaft, a pinion operable by the flexible joint, a transmission shaft extending in parallel spaced relation with the driving shaft, spaced gear wheels on the transmission shaft selectively engageable with said pinion to rotate the transmission shaft in either direction in response to rotation of the driving shaft in a constant direction, means for effecting selective engagement of the gear wheels and pinion, and operating mechanism operatively connected with the transmission shaft.

4. Mechanism of the character described including a transmission gear housing having an upstanding hollow cylinder, a second housing having a base end supported on the transmission housing and rotatable on the cylinder, a transmission shaft mounted for rotary and longitudinal movement in the transmission housing and projected into the chamber formed by said hollow cylinder, spaced gear wheels on the transmission shaft, a driving pinion between the gear wheels, means for shifting the transmission shaft

longitudinally to effect selective engagement of the gear wheels with said pinion, a second shaft journaled in the second housing, a coupling joint in the chamber for slidably connecting the transmission shaft with the second shaft to transmit rotation from one shaft to the other, and means for selectively latching the second housing from rotation on said cylinder.

5. Mechanism of the character described including a transmission gear housing having an upstanding hollow cylinder, a second housing having a base end supported on the transmission housing and rotatable on the cylinder, a transmission shaft mounted for rotary and longitudinal movement in the transmission housing and projected into the cylinder, spaced gear wheels on the transmission shaft, a driving pinion between the gear wheels, means for shifting the transmission shaft longitudinally to effect selective engagement of the gear wheels with said pinion, a second shaft journaled in the second housing and projecting into the cylinder, and a slidable connection between the two shafts to transmit rotation from one to the other.

25. 6. Mechanism of the character described including a transmission gear housing having an upstanding hollow cylinder, a second housing having a base end supported on the transmission housing and rotatable on the cylinder, a transmission shaft mounted for rotary and longitudinal movement in the transmission housing and projected into the cylinder, spaced gear wheels on the transmission shaft, a driving pinion between the gear wheels, means for shifting the transmission shaft longitudinally to effect selective engagement of the gear wheels with said pinion, a jaw on the transmission shaft, a second shaft journaled in the second housing, and a coupling joint on the second shaft including a pin having sliding operative connection with said jaw during shift of the transmission shaft.

7. In combination with a transmission gear housing, a transmission shaft mounted for rotary and longitudinal movement in said housing, means for rotating the transmission shaft selectively in either direction, means for shifting the transmission shaft longitudinally to determine its direction of rotation, an angular joint housing rotatably mounted on the transmission gear housing, a flexible joint including stub shafts rotatably mounted in opposite ends of the joint housing, and means slidably coupling one of said stub shafts with the transmission shaft to transmit rotation from the transmission shaft to said flexible joint.

8. In combination with operating mechanism including a shaft, driving and transmission shafts mounted for rotation on axes parallel with each other and angular to the shaft of the operating mechanism, means operatively connecting the driving and transmission shafts, means operatively connecting the transmission and operating mechanism shafts, and means for shifting the transmission shaft to vary its connection with the driving shaft and effect actuation of the operating mechanism in selected directions in response to rotation of the driving shaft in constant direction.

9. Mechanism of the character described including a transmission gear housing, a second housing having a base supported on the transmission housing, a cylindrical bearing fixed on one of said housings, a sleeve bearing fixed on the

other housing for engaging the cylindrical bearing to rotatably mount the second housing on the transmission housing, a transmission shaft mounted for rotatable and longitudinal movement in the transmission housing, spaced gear wheels on the transmission shaft, a driving pinion between the gear wheels, means for shifting the transmission shaft longitudinally to effect selective engagement of the gear wheels with said pinion, a second shaft journaled in the second housing, and a coupling joint operably connected with the transmission shaft to transmit rotation from one shaft to the other.

10. Mechanism of the character described including a transmission gear housing, a second housing having a base supported on the transmission housing, a cylindrical bearing fixed on one of said housings, a sleeve bearing fixed on the other housing for engaging the cylindrical bearing to rotatably mount the second housing on the transmission housing, a transmission shaft mounted for rotatable and longitudinal movement in the transmission housing, spaced gear wheels on the transmission shaft, a driving pinion between the gear wheels, means for shifting the transmission shaft longitudinally to effect selective engagement of the gear wheels with said pinion, a second shaft journaled in the second housing, and a coupling joint operably connected with the transmission shaft to transmit rotation from one shaft to the other.

11. Mechanism of the character described including a transmission gear housing, a second housing having a base supported on the transmission housing, a cylindrical bearing fixed on one of said housings, a sleeve bearing fixed on the other housing for engaging the cylindrical bearing to rotatably mount the second housing on the transmission housing, a transmission shaft mounted for rotatable movement in the transmission housing, spaced gear wheels on the transmission shaft, a driving pinion between the gear wheels, means for effecting shifting movement of the gear wheels to effect selective engagement of the gear wheels with the pinion, a second shaft journaled in the second housing, and a coupling joint operably connected with the transmission shaft to transmit rotation from one shaft to the other.

12. Mechanism of the character described including a transmission gear housing, a second housing having a base supported on the transmission housing, a hollow cylindrical bearing fixed on one of said housings, a sleeve bearing fixed on the other housing for engaging the cylindrical bearing to rotatably mount the second housing on the transmission housing, a transmission shaft mounted for rotatable movement in the transmission housing, spaced gear wheels on the transmission shaft, a driving pinion between the gear wheels, means for effecting shifting movement of the gear wheels for selective engagement with said pinion, a second shaft journaled in the second housing, and a coupling joint housed within said hollow cylindrical bearing and connecting said shafts to transmit rotation from one shaft to the other.
